UNITED STATES PATENT OFFICE

2,460,088

MEANS FOR ADJUSTING CLOTHESLINES

Donald E. Hutchings, Toronto, Ontario, Canada

Application January 30, 1945, Serial No. 575,241

1 Claim. (Cl. 211—119.02)

1

This invention relates to a means for adjusting clotheslines, and more particularly to such a means adapted to raise and lower a line as desired.

A primary object of this invention is the provision of an improved device adapted to raise and lower a clothesline, in such manner that the clothes may be readily placed thereon to ground level, and subsequent to placement of the clothes thereon the entire line may be raised to a relatively high position in such manner that the clothes are substantially out of the way and that space therebeneath may be utilized as desired.

An additional object of the invention is the provision of such a device which will be sturdy and durable in construction, reliable and efficient in operation, and relatively simple and inexpensive to manufacture and install.

Other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a side elevational view of a complete clothesline embodying the means for adjusting the same comprising the instant invention, various positions of adjustment being indicated by dotted lines.

Figure 2 is an enlarged sectional view taken substantially along the line 2—2 of Figure 1 as viewed in the direction indicated by the arrows.

Figure 3 is a bottom plan view of a constructional detail.

Figure 4 is an enlarged plan view of an additional constructional detail, and

Figure 5 is an enlarged constructional detail view, certain concealed parts thereof being indicated in dotted lines.

Similar reference characters refer to similar parts throughout the several views of the drawings.

Having reference now to the drawings, there is generally indicated at 10 a side wall of a building or the like, to which is adapted to be secured the device comprising the instant invention, and spaced a suitable distance from which is a line supporting post 11 or other desired device for supporting the opposite end of the clothesline.

Secured to the post 11 as by a hook 12 is a pulley 13, about which is passed a double line 14, the opposite end of which surrounds a pulley 15, secured to a hook 16 comprising a por-

2

tion of a movable block 17. As best shown in Figures 2 and 3, the block 17 comprises a member U-shaped in cross section, across the legs of which are positioned tapered rollers 18 mounted for rotation on axles 19. The block 17 is adapted to be positioned about a pipe or rod 20, secured to the side of the building 10 and angled outwardly therefrom toward its lower end. An eye 21 adapted to be secured as by a threaded extremity 22 into the side wall of the building 10 supports the upper end of the pipe, and the lower end thereof is supported by and secured to a member 23 comprising angularly disposed side portions 24 and a base plate 25 angled downwardly therefrom, the extremities of the members 24 and 25 being flanged as at 26 and 27, respectively, and adapted to be secured to the wall of a building as by means of screws or bolts 28. The lower extremity of the pipe 20 may be seated in a suitable aperture 30 in the extremity of the member 25.

The upper extremity of the member 17 is provided with an eye 31 to which is secured the extremity of a rope 32 which extends over a pulley 33 suspended at a substantial distance above the extremity of the pipe 20. The rope is in the form of a loop and extends downwardly beneath the member 23, and is adapted, when the line is in raised position, to be secured to a hook 35 secured to one of the members 24.

From the foregoing the operation of the device should now be readily understandable. When it is desired to place clothes on the line, the rope 32 is released from the hook 35 and the assembly 17 is permitted to slide by gravity to the lowermost portion of the pipe or rod 20. This places the line 14, at one end, within easy reach of an operator on the ground, whereupon the clothes may be positioned thereon, and by moving the line about the pulleys 13 and 15 successively move them toward the pulley 13 and the post 11. When the line is fully laden, the rope 32 may be pulled and by virtue of the pulley 33, lifts the assembly 17 and its associated pulley 15 upwardly to the position shown in full lines in Figure 1. Thereupon the rope may be wrapped or otherwise secured about the hook 35, and the clothes supported at a suitable level above the ground.

Obviously, the line 14, as well as the pipe 20 may be of any desired length, in order to provide the desired distance for raising and/or lowering the clothes.

Now from the foregoing it will be seen that there is herein provided a device accomplishing all the objects of this invention and others in-

cluding many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

In combination, a clothesline having one end 10 fixedly supported, an adjustable support for the other end thereof, said adjustable support including a vertically inclined tubular guide and a block freely slideable on said guide, said block having legs embracing said guide, a plurality of pins extending between said legs, a pair of roller means on each pin for engaging said guide, said roller means consisting of a pair of tapered rolls with their smaller diameters adjacent each other for maintaining bearing at two arcuately spaced 20 points on the circumferences of said guide, means

for raising and lowering said block on said guide comprising a pulley mounted above said guide, a cable attached to said block and entrained over said pulley and a bracket for supporting the lower end of said guide and for detachably securing said cable to maintain said block in vertically adjusted portions.

DONALD E. HUTCHINGS.
